(57) **CLAIM**

The ornamental design for a distal tip of an atherectomy/thrombectomy catheter with suction port, as shown and described.

DESCRIPTION

FIG. 1 is a perspective view of a distal tip of an atherectomy/thrombectomy catheter with suction port in accordance with the new design;

FIG. 2 is a front view thereof; and,

FIG. 3 is a side view thereof.

The features shown in the broken lines shown in FIGS. 1-3 depict environmental structure only and form no part of the claimed design.
